CIRCUIT FOR IMPROVING OSCILLATOR
STABILITYOrville E. Dow, Port Jefferson, N. Y., assignor to
Radio Corporation of America, a corporation of
Delaware

Application June 10, 1942, Serial No. 446,457

13 Claims. (Cl. 250—36)

1

My present invention relates to ultra high frequency circuits. One general object of my invention is to provide improved methods and means for controlling the flow of ultra high frequency waves.

In certain systems utilizing ultra high frequency waves it becomes necessary to turn off an ultra short wave generator and subsequently turn it on as, for example, in a duplex or half duplex system where the transmitter is turned off during the receiving period. In such cases, if control of the waves is accomplished by switching on and off operating voltages applied to the electron discharge device generator, large frequency drifts of the carrier occur when the transmitter is returned to the air after an interval of inactivity. This change in frequency becomes exceedingly large and objectionable when operating at frequencies above 500 megacycles and the condition is aggravated at frequencies above 1000 megacycles.

I have found that this frequency shift or drift is due in large measure to the change in heating of the low loss frequency determining circuits employed in the generator as it is turned on and off. This change in frequency, therefore, could be substantially reduced by building low or zero temperature coefficient frequency determining circuits, but in most instances the cost of such circuits is not justified.

In accordance with my present invention, this difficulty is circumvented by utilizing the usual low loss resonator or tank circuit for frequency control and maintaining the power dissipated therein substantially constant in both the "on" and "off" conditions of the oscillation generator. In this way, the temperature of the frequency controlling element is maintained substantially constant and, accordingly, the frequency of oscillations generated after a period of inactivity is substantially the same as the frequency of oscillations generated prior to the time the transmitter was turned off.

Further in accordance with my invention, I turn off the high frequency oscillator by detuning the tank circuit. For this purpose I make use of a section of transmission line for loading and unloading the tank circuit, as will be explained more fully hereinafter, whereby the tank circuit may easily be returned to its original frequency setting.

It will be noted that the detuning control described herein is especially useful for frequencies above 1000 megacycles where the oscillator efficiency is generally low. Hence in these cases the percent increase in power dissipated in the oscil-

2

lator when changed from the oscillating to the non-oscillating condition will be small.

Further, I have found that when the oscillator is turned off by detuning in accordance with what has been said above, the power dissipated in the tank or frequency controlling circuit may not be the same as the power dissipated in the circuit under oscillating conditions. Accordingly, my invention further contemplates the simultaneous detuning of the low loss tank circuit together with a change in voltage away from the optimum applied to certain electrodes of the generator. In this way, adjustments may be made so that the frequency of operation is maintained substantially constant despite on and off switching of the system.

Further objects, features, advantages and other factors to be considered in connection with my present invention will be given with the aid of the accompanying drawings which, however, are not to be construed as limiting the principles of my present invention and wherein:

Figures 1 and 1a are schematic diagrams of a self-oscillating Klystron oscillator as employed in a half duplex system. The drawing diagrammatically illustrates means for simultaneously loading the tank circuit by means of a section of a transmission line and increasing the plate voltage so as to cause cessation of oscillations when the antenna is switched to the receiver;

Figure 1 illustrates an open-circuiting switch for line 7, while Figure 1a illustrates a short-circuiting switch for line 7 when the system is in the receiving position;

Figure 2 diagrammatically illustrates a section of transmission line employed in connection with the system shown in Figure 1;

Figure 3 goes into greater detail and shows the mechanical construction of an adjustable length of coaxial line which may be used in connection with the system of Figure 1;

Figures 4 and 5 are cross-sectional and bottom views of a switch which may be used at S1 in Figure 1; and

Figure 6 illustrates a modified arrangement of Figure 1.

Referring to Figure 1, there is illustrated schematically a Klystron self-oscillator and its associated equipment. The tube 1, which is known as a velocity modulation tube, comprises a cathode 2, a control grid 3, a dual resonator structure 4, of which *a* is the input gap, *b* the output gap, and *c* the drift chamber, and collector electrode 5. Feedback is accomplished by means of the coupling loop CL. The first resonator nearest said

cathode is often referred to as a buncher, while the second resonator nearest the collector 5 is often referred to as a catcher.

The plate voltage supply E_1 subjects the cathode 2 to a negative potential with respect to the tank or plate 4 which is grounded at G_1 . The positive terminal of plate voltage source E_1 is grounded through variable resistor R_1 . The collector voltage is diagrammatically illustrated at E_2 and the control grid voltage at E_3 .

The carrier wave generated by the system of Figure 1 is modulated by the modulator 8 which may feed through transformer T a sub-carrier wave which may contain the signal as an amplitude modulation, a frequency modulation, a phase modulation or a constant frequency variable dot (CFVD) modulation.

Antenna 6 is connected to switch S_1 through the concentric transmission line ACL. The receiver RC is connected to switch S_1 through the concentric transmission line RCL and the transmitter or low loss tank circuit 4 is connected to the switch S_1 by means of loop L and line section 7. The antenna 6, by means of switch S_1 , of course, may be switched to either the receiver or transmitter.

In the half duplex system shown in Figure 1, the transmitting and receiving frequencies are the same or very nearly the same. Usually, because of its cost, elaborate shielding is not provided to prevent radiation directly from the transmitting oscillator to the receiver. Hence, it will be necessary to prevent the velocity modulation tube from oscillating during the receiving interval. Later, when transmitting it will be desirable to turn the velocity modulation tube on so that it operates immediately at its assigned or desired frequency.

In accordance with my invention, oscillations are stopped when the switch S_1 is open-circuited at its upper terminal T_1 , and the antenna 6 connected to the lower or receiving terminal T_2 , in turn connected to the receiver. In other words, when the switch S_1 is in the receiving position the transmission line section 7 is open-circuited at point T_1 . This places a reactive load on the oscillator instead of the resistive load which is present when the line 7 is connected to and matched to the antenna 6.

With point T_1 of transmission line section 7 open, transmission line section 7 will change the tuning of the resonator 4. The amount of detuning will depend upon the value of the reactive load which, in turn, will depend upon the length of line 7 between the loop L and point T_1 . As this length of line or section of line between L and T_1 is varied, the reactive load which this line section places upon resonator 4 will change continuously from a high (depending on the Q of the line) negative reactance through zero to a high positive reactance. At some point the resulting detuning of the resonator 4 will stop the oscillations. In Fig. 1, the length of line 7 from the tank circuit to point T_1 is given by the relation

$$\left(\frac{2N-1}{4}\right)\lambda$$

where λ is the operating wavelength and N is an integer. This length is further mentioned hereinafter.

When the switch S_1 is placed back in the "transmit" position so as to connect the antenna 6 through line ACL and section 7 to the resonator 4, the loading on the oscillator will be normal, assuming the transmission line 7 and ACL to be

matched to the antenna load. In this way I have provided a means for stopping the oscillator by detuning the resonator 4 and of easily and accurately returning it to its original tuning point.

It is to be noted that the condition of constant heating of the resonator 4 for the on and off periods will depend upon certain characteristics of the oscillation generating system. In a particular Klystron oscillator which I have employed, 5 I have found that the plate efficiency was about 5%. The plate input power (100 watts) was the same for the oscillating or non-oscillating condition when using the detuning method for stopping oscillations, as explained in connection with Figure 1. Thus, the plate input power dissipated in the resonator changed from 95 watts to 100 watts when oscillations were stopped. I also found that when the transmitter was started again the frequency was high. Hence, although the detuning method described stopped oscillations it did not in and of itself provide all of the frequency stability which was desired.

In accordance with another feature of my invention, frequency stability is enhanced by simultaneously increasing the plate voltage during the off period. In this way a condition is obtained whereby the frequency at the beginning of the transmitting period is very nearly the same as that at the end of the previous transmitting period.

30 Schematically, the system for increasing the plate voltage when a section of line is used to detune the tank is shown in Figure 1. Switch S_2 is uni-controlled with switch S_1 so that when point T_1 is open-circuited, R_1 is short-circuited by switch S_2 , thereby increasing the voltage impressed upon the tank or resonator 4 relative to the cathode. The value of R_1 in series with the plate voltage source E_1 can be adjusted to give the desired compensation. In a practical circuit the source of voltage E_1 may comprise a conventional rectifier and R_1 may be placed in the primary winding of the rectifier plate transformer.

40 The action of the increased voltage to enhance 45 frequency stability may be explained when it is considered that not only the total power dissipated in the resonator 4, but the distribution of this power in the resonator and the consequent thermal condition of the resonator will determine its resonant frequency. The paths of the electrons will be changed in the oscillating conditions from what they are in the non-oscillating condition due to the radio frequency voltages set up across the gaps a and b. This will result in a re-distribution of heating in the resonator from the "on" condition to the "off" condition. I have found, as explained above, that this re-distribution of heating can be in part compensated for by a change in amount of heating and this amount of heating may be varied by varying the voltage to which the plate and cathode are subjected in the off and on periods of the oscillator.

For one particular setting of the oscillator I have found the following plate voltages to maintain the carrier frequency substantially the same at the beginning of a transmission period as it was at the end of the previous transmission period with, of course, the use of a transmission line section for detuning:

70 Oscillator on Plate voltage=1600 Plate current=67 MA
Oscillator off Plate voltage=1775 Plate current=67 MA

75 It is to be noted that an additional advantage of changing the voltage E_1 , to which a pair of electrodes of the oscillator are subjected, results from a characteristic of the velocity modulation

tube to the effect that for a particular operating frequency there is a certain value of plate voltage at which the Klystron operates best. If this voltage is changed from this optimum value, oscillations may be more easily stopped by detuning. 5 The direction of the voltage change and the detuning should be such as to aid rather than oppose each other.

It should also be noted that switch S_1 , as will be described more fully later in connection with Figures 4 and 5, can be so constructed that the output end of line section 7 is short-circuited during the receiving period. The length of the transmission line section 7 in this case should be made one-quarter wave length longer or shorter when short-circuited at T_1 than when open-circuited at T_1 . Such an arrangement is shown in Fig. 1a. If it is desired to impress a maximum load upon the tank circuit 4 by means of the line section 7, the section 7 should be effectively an odd number, including one, of quarter wave lengths long when point T_1 is open-circuited and an odd number, including one, of half wave lengths long when point T_1 on the inner conductor 10 IC is short-circuited to the outer conductor OC. In Fig. 1a the switch S_1' is similar to the one shown in Figs. 4 and 5 of my United States Patent 2,426,186 granted August 26, 1947. The cylinder 35 is the same as the correspondingly numbered part in Fig. 4. The switches S_2 and 15 S_1' are shown in the receive position. The antenna is connected to the receiver and transmission line 7 is shorted at T_1 by means of the cylinder 35 which makes contact to the shell of the switch. In the transmitting position, the elbow 20 in the cylinder 35 is rotated 180° so the antenna is connected to the terminal T_1 of line 7, and switch S_2 is opened. The receiver-transmission line terminal T_2 will then be shorted. As explained herein, the length of line 7 will be 25 different with this switch than with the switch shown in Fig. 1.

Transmission line 7 should be adjustable in length to obtain the best performance. A transmission line whose length is adjustable may be constructed as shown in Figure 2. The outer conductors are 21 and 23, the inner conductors are 22 and 24. The transmission of R.-F. energy is from 24 to the junction J of 24 and 22 and then to the right on 22. Metal rods 26 and metal sleeve MS are supported by and mounted upon metal sleeve 25 and make sliding contact to inner conductor 22 and are spaced one-quarter wave length from the sliding junction of 22 and 24. It is to be noted that 26 may be a metal disc with ears protruding through the slots in the hollow conductors. Sleeve 25 is connected to the outer conductor 23 and makes sliding contact with outer conductor 21. Outer conductor 21 is slotted at S_1 for accommodating the ears on disc 26 or for the bars or rods 26 and also slotted for inner conductor 24 so that the adjustment in line length may be slightly more than one-half wave length. Sleeve 25 is long enough to completely cover the slots SL in 21 at any position. The location of short-circuiting rods 26 with respect to 24 may be adjustable so the line may be used over a range of frequencies. Insulators 27 are spaced one-quarter wave length apart to compensate the reflections caused by them individually.

An adjustable length coaxial line of different construction is shown in Figure 3. This was built to operate at a frequency of about 3000 mc. Both the inner IC and outer OC conductors are of tele-

scoping tubing. The "Victron" insulators are in pairs spaced one-quarter wave length apart to compensate for reflections. This type of construction does not result in a uniform line, but the variations in characteristic impedance along its length is not generally serious. This adjustable section was used between two lengths of flexible coaxial cable.

Figures 4 and 5 show a form the switch S_1 of Figure 1 may take. Figure 4 is a cross-section of the switch and Figure 5 is a bottom plan view. Care has been taken to keep the coupling low between coaxial fittings 31, 32 and 33. 31 may be the coaxial cable or line section 7 to the transmitter of Figure 1, 32 goes to the receiver and 34 is the connection to the antenna. The fitting 33 (see Figure 5) is a spare. This switch was constructed for operation at about 3000 mc. The insulators are in pairs spaced one-quarter wave length apart. The plug or piston 35 may be rotated by means of handle 36 within cylinder 37. The spring washer 39 insures good contact of the ends of piston 35 with the bottom of cylinder 37 and its cover plate 38. The outer conductors OC of fittings 31, 32, 33 and 34 are soldered into cylinder 37. The inner conductors IC of 31, 32 and 33 are held rigidly in place by their insulators and have spring chucks at their outer ends to receive #13 gauge wire and have slots at their inner ends to receive the blade at the end of the inner conductor of 34. The inner conductor of 34 is held by insulators 40, 42 rigidly within the elbow 44 drilled in piston 35. Hence, when 35 is rotated the inner conductor of 34 rotates and engages in turn the inner conductors of 31, 32 and 33. There is a bearing or rotating contact between the inner conductor of 34 and the inner conductor of the cable or transmission line connected to 34. About the circumference of 35 is a groove 48 the width of which is equal to the diameter of the inner conductors of 31, 32 and 33. The sides of this groove make contact with and ground the inner conductors of the two coaxial lines not connected to 34.

In Figure 6 the transmission line section 50 used to turn the oscillator on and off is independent of the transmission line 52 leading to antenna 6. In the oscillating condition shown, with the far end FE of the line section grounded by switch S_1 , 45 the effective length of line 50 from loop L to the grounding point FE should be an odd number, including one, of quarter wave lengths. Then, when switch S_1 is opened, the loading will be found to increase to such an extent as to stop the generation of oscillations.

As an alternative, oscillation generation may be made to stop with the switch S_1 closed and S_2 closed by making the effective length of the line section between L and FE effectively equal to an 50 odd number, including one, of half wave lengths, such lengths being taken at the desired operating frequency.

Having thus described my invention, what I claim is:

1. High frequency apparatus comprising a multi-electrode electron discharge device and a resonator circuit therefor electrically and thermally connected thereto, a section of transmission line coupled to said resonator, means for applying a potential to a pair of electrodes of said device to cause sustained oscillations in said resonator circuit with said section of line coupled thereto at a resonant frequency dependent on the thermal condition of said resonator circuit, and means simultaneously to terminate said section of trans-

mission line with an impedance and at a point chosen to load said resonator circuit to non-resonance to prevent oscillations therein and to apply a potential to said pair of electrodes to improve the stability of the thermal condition of said resonator circuit whereby the frequency stability of said apparatus upon the generation of oscillations immediately after periods of non-oscillation is improved.

2. High frequency apparatus comprising a multi-electrode electron discharge device and a resonator circuit therefor electrically and thermally connected thereto, means for applying a potential to a pair of electrodes of said device to cause sustained oscillations in said resonator circuit at a resonant frequency dependent on the thermal condition of said resonator circuit, a section of transmission line coupled to said resonator for coupling said resonator to a utilization circuit, and means simultaneously to terminate said section of transmission line with an impedance and at a point chosen to load said resonator circuit to non-resonance to prevent oscillations therein and to apply a potential to said pair of electrodes to improve the stability of the thermal condition of said resonator circuit whereby the frequency stability of said apparatus upon the generation of oscillations immediately after periods of non-oscillation is improved.

3. The apparatus claimed in claim 2, said point being an integral number of electrical quarter wave lengths distant from the point of electrical coupling of said transmission line to said tank circuit at said resonant frequency.

4. The apparatus claimed in claim 2, said point being an odd integral number of electrical quarter wave lengths distant from the point of electrical coupling of said transmission line to said tank circuit at said resonant frequency, said terminating impedance being a short circuit.

5. The apparatus claimed in claim 2, said point being an even integral number of electrical quarter wave lengths distant from the point of electrical coupling of said transmission line to said tank circuit at said resonant frequency, said terminating impedance being an open circuit.

6. High frequency apparatus comprising a multi-electrode electron discharge device and a resonator circuit therefor electrically and thermally connected thereto, means for applying a first potential to a pair of electrodes of said device to cause sustained oscillations in said resonator circuit at a resonant frequency dependent on the thermal condition of said resonator circuit, a section of transmission line coupled to said resonator for coupling said resonator to a utilization circuit, and means simultaneously to terminate said section of transmission line with an impedance and at a point chosen to load said resonator circuit to non-resonance to prevent oscillations therein and to apply a second potential to said pair of electrodes greater than said first potential to improve the stability of the thermal condition of said resonator circuit whereby the frequency stability of said apparatus upon the generation of oscillations immediately after periods of non-oscillation is improved.

7. The apparatus claimed in claim 2, said resonator circuit comprising a cavity resonator.

8. High frequency apparatus comprising a multi-electrode electron discharge device and a resonator circuit therefor electrically and thermally connected thereto, means for applying a potential to a pair of electrodes of said device to cause sustained oscillations in said resonator circuit at a

resonant frequency dependent on the thermal condition of said resonator circuit, a utilization circuit, a section of transmission line coupling said resonator circuit to said utilization circuit, and means simultaneously to terminate said section of transmission line with an impedance and at a point chosen to load said resonator circuit to non-resonance to prevent oscillations therein and to apply a potential to said pair of electrodes to

improve the stability of the thermal condition of said resonator circuit whereby the frequency stability of said apparatus upon the generation of oscillations immediately after periods of non-oscillation is improved.

15. 9. The apparatus claimed in claim 8, said resonator circuit comprising a cavity resonator as an integral part of said electron discharge device.

10. High frequency apparatus comprising a multi-electrode electron discharge device and a cavity resonator therefor electrically and thermally connected thereto as an integral part thereof, means for applying a potential to a pair of electrodes of said device to cause sustained oscillations in said cavity resonator at a resonant

25 frequency dependent on the thermal condition of said cavity resonator, a utilization circuit, a section of transmission line coupling said cavity resonator to said utilization circuit, a short-circuiting element for short-circuiting said transmission line, and a switch mechanically coupled to said short-circuiting element to terminate said section of transmission line with a short-circuit at a point chosen to load said resonator circuit to non-resonance to prevent oscillation thereof and simultaneously to apply a potential to said pair of electrodes to improve the stability of the thermal condition of said resonator circuit whereby the frequency stability of said apparatus upon the generation of oscillations immediately after periods of non-oscillation is improved.

40 11. High frequency apparatus comprising a multi-electrode electron discharge device and a resonator circuit therefor electrically and thermally connected thereto, a resistor, a source of potential, said source, said resistor and a pair of said electrodes being serially connected to apply a potential to said pair of electrodes to cause sustained oscillations in said resonator circuit at a resonant frequency dependent on the thermal condition of said resonator circuit, a utilization circuit, a section of transmission line coupling said resonator circuit to said utilization circuit, and means simultaneously to terminate said section of transmission line with an impedance and at a point chosen to load said resonator circuit to non-resonance to prevent oscillation thereof and to short-circuit said resistance to apply a second potential to said pair of electrodes greater than said first potential to improve the stability 50 of the thermal condition of said resonator circuit whereby the frequency stability of said apparatus upon the generation of oscillations immediately after periods of non-oscillation is improved.

65 12. The apparatus claimed in claim 11, said resonator circuit being a cavity resonator which is an integral part of said electron discharge device.

70 13. The apparatus claimed in claim 11, said electron discharge device comprising first and second cavity resonators each having a gap therein, a cathode positioned outside the field of said first cavity resonator, a collector positioned outside the field of said second resonator, said resonator circuit comprising said cavity resonators, said

pair of electrodes being said cathode and said collector, said transmission line being coupled to the interior of said second cavity resonator.
